CLAIM

USPC D2/860, 861, 700, 702, 703, 704, 706,

The ornamental design for a one-piece swimsuit, as shown

D2/708, 720, 721, 728, 731, 732, 733,

and described.

D2/734, 735, 736, 737, 738, 840

DESCRIPTION

CPC A41D 1/06; A41D 1/062; A41D 1/065;

FIG. 1 is a front view of a one-piece swimsuit showing my new design;

A41D 1/067; A41D 1/08; A41D 1/082;

FIG. 2 is a rear view thereof;

A41D 1/084; A41D 1/085; A41D 1/088;

FIG. 3 is a left side view thereof; and,

A41D 1/089; A41D 13/02; A41D 13/04;

FIG. 4 is a right side view thereof.

A41D 2600/20; A41D 2600/202; A41D

The broken line outline of a model assists in illustrating how

7/00; A41D 7/006; A41D 2400/38; A41D

the one-piece swimsuit may appear when in a position of

10/00; A41C 1/02; A41C 1/10; A41C

use, but forms no part of the claimed design. The dash-dot-

1/12; A41C 3/00; A41C 3/0014; A41C

dash-dot-dot broken lines define the bounds of the one-piece swimsuit and form no part of the claimed design. All other broken lines depict features of the one-piece swimsuit that form no part of the claimed design.

3/08
